UNITED STATES PATENT OFFICE

2,401,578

BOTTLE CARRIER

John E. Miller, Chicago, Ill.

Application June 10, 1944, Serial No. 539,635

2 Claims. (Cl. 224—45)

1

The object of my present invention is to provide a simple, efficient, and low cost carrier for bottles such, for instance, as commonly used for soft drinks, the construction being such that it may be applied and used by the average consumer to extract a plurality of such bottles simultaneously from the usual shipping container, transport the bottles to desired point of use, and return them empty into the shipping container.

The accompanying drawing illustrates my invention, in which

Fig. 1 is a perspective view of the empty carrier;

Fig. 2 is a side elevation of the carrier and associate group of bottles in an intermediate stage of application of the carrier to the bottles; and

Fig. 3 is a fragmentary sectional detail.

In the drawing 10 indicates a main body plate of any suitable material, perforated by perforations 11 spaced in accordance with the usual bottle spacing in common shipping containers and of a diameter permitting projection of the bottle necks therethrough. Most conveniently, two parallel rows of three perforations each are provided so that the carrier may be utilized for a group of six bottles.

At one end of each longitudinal series of perforations is hinged a spring retainer composed of two substantially parallel wires 12, 12, each kinked at points intermediate its length adjacent the perforations 11, as indicated at 13, so as to be capable of snapping over the mouths of the bottles and springing under the bottle shoulders immediately subtending the mouth. The outer ends of wires 12, 12 are secured together by spot welding or other suitable welding means and bent to form a latch 14 cooperative with the adjacent edge of plate 10.

Plate 10 is provided with a suitable handle 15 on which the plate is balanced.

The operator, grasping handle 15, may project the plate downwardly over a group of six bottles in the usual shipping container so that the perforations 11 will pass over the mouths of the bottles and downwardly on their necks thus displacing the retainers 12 upwardly, as illustrated in Fig. 2. The operator may then swing the retainers downwardly over the mouths of the bottles, the portions 13 thereof first springing outwardly and then inwardly under the bottle mouth, whereupon the group of bottles may be readily extracted from the shipping container and carried to any desired point.

It will, of course, be understood that the retainers 12 may be so attached to the plate 10 that, instead of swinging upwardly as described, the wires 12 will merely yield laterally to permit

2

the portions 13 to spring first outwardly and then inwardly to retain the bottles in place relative to the plate 10, but the construction illustrated is preferable because the operator, before extracting the bottles from the carrier, may free the latch end of the retainer from the plate and swing the same upwardly to withdraw the retainer from the bottle necks more readily than he could force the retainer wires apart sufficiently to release a bottle.

In order to facilitate storage and shipping of the carrier, handle 15 is formed of wire, generally U-shaped, with its legs threaded through perforation 10' in plate 10, and withdrawal is prevented by the laterally deflected tips 15'. At the base of the U, the arms are deflected, as shown at 15'', and the plate distorted at the perforations, as indicated at 10'', so that the handle may be moved to the storage position indicated by dotted lines in Fig. 3.

I claim as my invention:

1. A bottle carrier comprising a main body plate, formed at a plurality of points with perforations arranged in longitudinal series and capable of freely passing bottle necks in a common spaced relationship, and a spring retainer associated with each longitudinal series of said perforations, comprising substantially parallel spring wires kinked at points intermediate the wire length and immediately adjacent the perforations in such manner that the bottle necks may be projected between the wires at the kinked points and the kinked portions of the wires will spring under the neck shoulders when said wires lie substantially parallel with the plate, and a hinge connection between one end of each retainer structure and the body plate whereby the free end of the retainer structure may be swung away from the plane of the body plate.

2. A bottle carrier comprising a main body plate, formed at a plurality of points with perforations arranged in longitudinal series and capable of freely passing bottle necks in a common spaced relationship, and a spring retainer associated with each longitudinal series of said perforations, comprising substantially parallel spring wires kinked at points intermediate the wire length and immediately adjacent the perforations in such manner that the bottle necks may be projected between the wires at the kinked points and the kinked portions of the wires will spring under the neck shoulders when said wires lie substantially parallel with the plate, each pair of wires being hinged at one end to the body plate, so that the free ends of said pairs may be swung away from the plane of the body plate.

JOHN E. MILLER.
